UNITED STATES PATENT OFFICE.

JEAN D. HAZEN, OF SARASOTA, FLORIDA, ASSIGNOR OF ONE-HALF TO OWEN BURNS, OF SARASOTA, FLORIDA.

CARBURETER.

1,132,580.

Specification of Letters Patent. Patented Mar. 23, 1915.

Application filed September 4, 1913. Serial No. 788,149.

To all whom it may concern:

Be it known that I, JEAN D. HAZEN, a citizen of the United States, residing at Sarasota, in the county of Manatee and 5 State of Florida, have invented new and useful Improvements in Carbureters, of which the following is a specification.

The present invention relates to carbureters, and one of the primary objects is to 10 provide means, whereby water will be admitted to constitute a part of the charge, such water commingling with the air prior to the introduction of the hydrocarbon fuel.

Another object is to provide a carbureter, 15 by means of which fuel of different characteristics, as for example, kerosene oil and gasoline may be used, provision being made for a proper supply of each fuel and the necessary regulation thereof.

20 In the accompanying drawings: Figure 1 is a view partly in section and partly in elevation of a carbureter, embodying the present invention. Fig. 2 is a top plan view of the same with the cover of the casing removed. Fig. 3 is a detail sectional view illustrating the controlling means for the fuel. Fig. 4 is a detail sectional view on the line 4-4 of Fig. 1. Fig. 5 is a detail view of one of the shut-off valves for the 25 fuel. Fig. 6 is a detail sectional view of the means for varying the resistance of the tension spring that opposes the air inlet controlling valve. Fig. 7 is a detail sectional view of one of the supply controlling valves 30 and its associated parts. Fig. 8 is a similar view of the other supply controlling valve.

Similar reference numerals designate corresponding parts in all the figures of the drawings.

40 In the embodiment illustrated, a casing is employed comprising a cup-shaped body 9 having an integral top flange 10, to which is secured by means of screws 11, or other suitable fasteners, a removable cover 12.

45 This cover is provided with a central up-standing nipple 13 that is internally threaded, as shown at 14, whereby it may be suitably coupled to an engine or other article to receive the prepared charge. The body 9 of the casing is provided with a central up-standing charge-forming and directing conduit 15 that depends from the bottom of said casing in the form of an exteriorly threaded boss 16, while the upper end fits snugly in 55 a recessed seat 17 formed in the under side

of the cover or cap 12, so that the nipple 13 constitutes an extension or part of said conduit. The body of the casing is furthermore provided with a transverse partition 18 arranged radially of the conduit 15, and 60 separating the interior of said casing into two separate compartments or reservoirs 19 and 20, respectively intended for holding predetermined amounts of fuel of different characteristics, as for example kerosene oil 65 and gasoline. Each compartment is supplied with fuel through a laterally extending nipple 21 that can be connected by a pipe as 22, to any suitable source of supply. Each nipple at its juncture with the 70 casing is enlarged, as shown at 23, and is provided in its top with an opening 24 closed by a screw cap or plug 25. The nipples are interiorly threaded to receive plugs 26 having supply ports 27 therethrough, the 75 inner ends of such ports constituting valve seats, against which abut tapered valves 28. These valves are carried by stems 29 having ball heads 30 at their inner ends that are received in sockets 31 formed in bell crank 80 arms 32. The said balls are retained in the sockets by screws 33. The bell crank arms 32 are journaled on suitable pivots 34, on which are also journaled other crank arms 35, to which are fastened, by screws 36, or 85 other suitable devices, arcuate floats 37 that partially surround the conduit 15. The two arms 32 and 35 are thus relatively adjustable and are adjusted on screws 38 that are threaded through the arms 35 and are journaled in ears 39 formed upon the arms 32. These screws are readily accessible through the openings 24 when the caps 25 are removed, as will be evident, and it will thus be 90 seen that by rotating said screws in one direction or the other, the angular relation of the arms 32 and 35 can be altered, so that the level of the liquid fuel can be maintained at any height desired.

95 Arranged axially within the conduit 15 is a fuel-discharge nozzle 40 that is carried by transverse pipes 41 extending through the walls of the conduit and through the walls of the casing 9. The outer projecting ends of said pipes are provided with packing 100 glands 42, through which extend the stems 43 of needle valves 44, said stems having exposed actuating heads 45. By referring particularly to Fig. 3, it will be noted that 105 valve seats 46 are employed for the needle 110

valves 44, and it will also be noted that the ports controlled by such valves, are of different diameters, depending upon the character of the fuel used. The pipes 41 respectively 5 communicate with the compartments 19 and 20, through lateral inlet ports 41^a, and these ports are controlled by plug valves 42^a threaded, as shown at 43^a in Fig. 5 through the casing wall 9 and having suitable pack- 10 ing glands 44^a.

The outlet end of the conduit 15 is controlled by a throttle valve 47 journaled in theapple 13 and having its shaft 48 provided with an exposed actuating arm 49. 15 The air inlet to said conduit is disposed in angular relation thereto, as illustrated at 50, and is provided with a central guide element 51 having a valve stem-receiving bore 52. The inner end of the inlet is provided 20 with a suitable valve seat 53, with which co-operates an inwardly opening air-controlling valve 54. This valve is fixed to a sliding stem 55, one end of which slidably operates in the bore 52, the other end siding in 25 a tubular screw 56 threaded into a nipple 57 formed upon the inlet member. A coiled spring 58, interposed between and bearing against the valve 54 and the screw 56, serves to normally hold said valve in its closed position. It will be evident that by turning the screw 56 in one direction or the other, the tension of the spring 58 against the valve 30 may be varied. The guide member 51 is furthermore provided alongside the bore 50 35 with a water inlet port 59, with which communicate the bore of a nipple 60 that can be connected to any suitable source of water supply. The discharge end of the port 59 is controlled by the valve 54, and a needle 40 valve 61 is also employed for controlling the amount of water delivered or for shutting it off altogether. It will be evident that with this structure, a spray of water will be admitted to the conduit with the air at every 45 time a charge is drawn through the carbureter, and the amount of water so admitted can be easily controlled. It will also be

evident that different grades or different characters of fuel may be utilized with the same carbureter by shutting off one or the other of the compartments, and the supply from either compartment can be controlled and modified as desired. The level of the fuel in each compartment is at all times maintained by the float-controlled valve, and this level 50 can be varied at any time by relatively adjusting the float and valve-carrying arms 32 and 33. It will also be evident that the parts are always readily accessible, so that 55 they can be inspected, cleaned, and if necessary replaced with ease and expedition. 60

From the foregoing, it is thought that the construction, operation and many advantages of the herein described invention will be apparent to those skilled in the art, without further description, and it will be understood that various changes in the size, shape, proportion and minor details of construction may be resorted to without departing from the spirit or sacrificing any of the 70 advantages of the invention.

Having thus fully described my invention, what I claim as new, and desire to secure by Letters Patent, is:—

In a carbureter, the combination with an 75 air conduit having an inlet, of a central guide element in the inlet having a stem-receiving bore and a water discharge port located in said element alongside the bore, means for delivering water to the port, a 80 needle valve in the guide element controlling the water supply, an air valve controlling both the air inlet and the water discharge port, said valve having a stem sliding in the bore of the guide element, means 85 for yieldingly holding the valve closed, and means for supplying fuel to the conduit.

In testimony whereof I have hereunto set my hand in presence of two subscribing witnesses.

JEAN D. HAZEN.
